[57] CLAIM

The ornamental design for angel wings, as shown and
described.

DESCRIPTION

FIG. 1 is a front view of the angel wings, showing my new
design;

FIG. 2 is a rear view thereof;

FIG. 3 is a right side view thereof, the left plan view being
a mirror image thereof; and,

FIG. 4 is a top view thereof.

The broken line portions of FIGS. 1-4 are shown for
illustrative purposes only.
